CLAIM

The ornamental design for a juicer apparatus, as shown and described.

DESCRIPTION

FIG. 1 is a right side/top perspective view of a juicer apparatus in accordance with the subject technology.

FIG. 2 is a mirrored left side/top perspective view of the juicer apparatus of FIG. 1 in accordance with the subject technology.

FIG. 3 is a left side view of the juicer apparatus of FIG. 1.

FIG. 4 is a right side view of the juicer apparatus of FIG. 1.

FIG. 5 is a front view of the juicer apparatus of FIG. 1.

FIG. 6 is a back view of the juicer apparatus of FIG. 1.

FIG. 7 is a top view of the juicer apparatus of FIG. 1; and,

FIG. 8 is a bottom view of the juicer apparatus of FIG. 1.

The purpose of the broken lines shown in the drawings is to denote features of the structure that form no part of the claimed design.

1 Claim, 6 Drawing Sheets
